U.S. Cl. 424—212

3 Claims

ABSTRACT OF THE DISCLOSURE

This disclosure describes a method of treating warm-blooded mammals infected with endoparasitic helminths with a highly effective anthelmintic, dimethyl-2,2,2-trichloro-1-n-butyryloxyethylphosphonate, having low mammalian toxicity. The superiority of this compound compared to known organophosphonate anthelmintics is effectively demonstrated.

2

largely eliminated from the tissues of rats in a few days, (ref. Technical Brochure, Prentiss Drug and Chemical Co., Inc.). For example, 50–1500 mg./kg./day by oral administration, are effective, depending on the host animal and the extent of infection. Canines administered a single therapeutic dose of butonate in the range of about 200–800 mg./kg. did not display intolerable side effects; the anthelmintic effect was excellent.

Butonate has been shown to be highly effective in eliminating helminths common to canines, having an average endoparasite elimination in the order of 90–96% against the following: *Ancylostoma canium*, *Toxocara canis*, and *Trichuris vulpis*.

The following table indicates the high degree of anthelmintic effectiveness in dogs in a single dose of about 200 mg./kg. of butonate. Butonate was administered orally in capsule form at the time of feeding. No fasting or purgatives were employed. The dogs were necropsied at 72 hours and fecal counts were made.

INDIVIDUAL TESTING

Dog No.	Wt. in lbs.	Ancylostoma			Toxocara			Trichuris		
		Expd.	Left	Expd., percent	Expd.	Left	Expd., percent	Expd.	Left	Expd., percent

	Total	182	1		181	4		130	5	

This invention relates to a method of treating warm-blooded mammals infected with endoparasitic helminths, and specifically to the use of dimethyl-2,2,2-trichloro-1-n-butyryloxyethylphosphonate, hereafter "butonate," Cassida et al. (U.S. Pat. 2,911,435). This compound, having low mammalian toxicity, has been discovered to possess highly effective anthelmintic properties. Moreover, this invention relates to a method of treating mammals, infected with endoparasites, with butonate in a pharmaceutically acceptable sustained action dosage form.

In the treatment of mammals infected with endoparasites, several vital criteria must be achieved, including low toxicity in the host animal, toxicidal activity against the endoparasites therein and chemical stability in the digestive tract of the host animal. For example, other organophosphates have been known to be parasitocidal, but have been ineffective by oral application due to their tendency to be readily hydrolyzed in the digestive tract of the host animal.

The compound of this invention, butonate, has satisfied all the above mentioned criteria. In acute toxicity studies in adult white rats of the Sprague-Dawley strain, the oral LD₅₀ is about 1000–1600 mg./kg. Large oral doses are

50

GROUP EVALUATION

	Nematode range	Harbor average	Average percent expelled	Animals cleared
55	Ancylostoma.....	1-124	17	94.1
	Toxocara.....	1-70	14	97.2
	Trichuris.....	1-29	10	95.1

60

The required, effective dose of butonate can be incorporated in the animals' feed in the form of tablets, capsules, pellets, or the like, along with inert, pharmaceutically acceptable carriers. For example, for encapsulation, the following carrier materials may be used: lactose, starch, magnesium stearate and the like. For tabletting, the same may be used with or without such other materials as corn starch, corn starch (paste), dicalcium phosphate and calcium stearate.

65

70

A preferred method of preparing a suitable encapsulated dosage form is illustrated in the composition having the following content:

	Mg./capsule
(1) Butonate	100.00
(2) Dicalcium phosphate	100.00
(3) Lactose	98.00
(4) Corn starch	98.00
(5) Magnesium stearate	4.00
	10
	400.00

Procedure

Deposit #1 on #2 by gradually adding #1 dissolved in 100 ml. methylene chloride to #2 while mixing gently using a sigma mixer. When #1 and #2 are thoroughly mixed, pass the moist mass through an oscillating granulator using a #10 mesh screen. Allow the granules to air dry overnight. Blend granules #1 and #2 with #3, #4 and #5. Fill blend into #1 capsules.

A preferred method for preparing a suitable tableted dosage form is illustrated in the composition having the following content:

	Mgs. per tablet
(1) Butonate	100.00
(2) Magnesium trisilicate	100.00
(3) Corn starch	20.00
(4) Polyvinylpyrrolidine	10.00
(5) Guar gum	10.00
(6) Calcium stearate	2.50
	30
	242.50

Procedure

Deposit #1 and #2 by gradually adding #1 dissolved in 100 ml. methylene chloride to #2 while mixing gently using a sigma mixer. When #1 and #2 are thoroughly mixed, pass the moist mass through an oscillating granulator using a #10 mesh screen. Allow the granules to air dry overnight. The granules are then blended with #3 and this mixture is granulated with a 15% solution of #4 in 95% alcohol. The wet mass is passed through an oscillating granulator using a #14 screen. The wet granules are dried in a fluid bed drier. The dried granules are blended with #5 and #6. The mixture is then tableted using a suitable tablet press.

The presently preferred method is to include the dosage in a capsule and administer orally.

Butonate can be incorporated into a suitable sustained action dosage form which prolongs its effectiveness in the digestive tract of the host animal. A preferred method of preparing a suitable sustained dosage form is illustrated in the composition having the following content:

	Parts by wt.
(1) Stearyl alcohol	140
(2) Pyrogenic colloidal silica	60
(3) Butonate	100
	300

33.3% Butonate by weight.

Procedure

Stearyl alcohol is heated to about 80° followed by addition of pyrogenic colloidal silica and butonate. The reagents are intimately mixed to disperse and then cooled. After the mixture congeals, the mass is broken up by passing through an oscillating granulator equipped with a #8 mesh screen. The resulting granules, being 33.3% by weight of the active ingredient butonate, are incorporated into capsules for convenient administration.

Thus, a prolonged-acting anthelmintic such as butonate can be used in the treatment of warm-blooded mammals infected with endoparasites with a high degree of success. The dose would be determined on the basis of the degree of existing infection as well as the type of mammal being treated. Having eliminated the existing endoparasites from the host animal, butonate can also be used as a prophylactic, the dose being less than treatment of an infected animal, for example, 1-50 mg./kg./day; the dose, however, would again depend on the size and species of the mammal being treated.

From the foregoing description, one skilled in the art can easily ascertain the essential characteristics of this invention, and without departing from the spirit and scope thereof, can make various changes and modifications of the invention to adapt to various usages and conditions. Consequently, such changes and modifications are properly, equitably, and intended to be, within the full range of equivalence of the following claims.

What is claimed is:

1. A method of treating dogs internally infected with ancylostoma, toxocara and trichuris nematode worms comprising the step of orally administering an effective amount of a composition comprising dimethyl-2,2,2-trichloro-1-n-butyryloxyethylphosphonate and pharmaceutically acceptable carrier therefor.

2. A method as defined in claim 1 wherein said phosphonate compound is administered in an amount ranging from 100-1500 mg./kg./day.

3. A method of treating dogs comprising orally administering an effective amount of dimethyl-2,2,2-trichloro-1-n-butyryloxyethylphosphonate as a prophylactic against ancylostoma, toxocara and trichuris nematode worms.
